UNITED STATES PATENT OFFICE.

JEAN VICTOR HENRI BESSON, OF BOURGES, FRANCE.

RADIATOR AND THE LIKE.

Application filed April 23, 1928, Serial No. 272,152, and in France May 3, 1927.

The present invention relates to a self-contained radiator with water circulation by thermosiphon action, in which either electricity, or gas, spirit, or hydrocarbons of any kind are used as source of heat.

This radiator is mainly characterized in this that it consists of independent elements, each having their own heating and circulation.

10 The radiator may be made of a series of vertical tubes, connecting a lower tank containing the source of heat, or directly heated by it, with an upper tank, the bottom of the tanks being of such shape that a circulation of water is set up as a result of the difference in density from bottom to top in the centre tubes, and from top to bottom in the lateral tubes.

20 In a simpler manner, each radiator unit may consist of a flat cistern made by joining two metal plates at their edges by a folded seam or by soldering these edges, inside of which cistern partitions guide the circulating water while at the same time staying the plates of the container. The arrangement of the partitions inside the tank is such that an ascending current is produced in the centre of the apparatus while a descending current passes down the sides.

30 The cisterns or casings may be placed one in front of the other or show in plan a radial arrangement, the general form of the radiator usually being circular or semi-circular.

35 In such cases where electricity is used as source of heat, the heating may be regulated by a handle and contacts so as to permit of using a varying number of resistance units.

The invention will be better understood by 40 reference to the accompanying drawings showing by way of example several alternatives in which it is realized.

Figure 1 is a diagrammatic, vertical, longitudinal, sectional view of a radiator constructed and arranged in accordance with my invention.

Figure 2 is a transverse sectional view of the same on the plane indicated by the line II-II of Figure 1.

50 Figure 3 is a diagrammatic vertical lon-

gitudinal sectional view of a modified form of the same.

Figure 4 is a diagram showing a modification of the invention in which the cells are radially arranged.

55 Figure 5 is a detail diagrammatic sectional view of a modified construction.

Figure 6 is a similar view of the same on a plane at right angles to that of Figure 5.

Fig. 7 shows an apparatus with water 60 tubes.

The water which circulates inside each tank 1 is guided, directed and conducted by partitions 2, of any suitable number. The height of the said partitions is approximately 65 two thirds that of the unit, and their lower edge 2' may be slightly bent outwards in order to assist the water circulation (Fig. 3).

In cases where but two partitions are made 70 use of, they are arranged in such a manner as to leave between them a central passage 3 of at least equal width to, and in practice preferably greater than, the added widths of the lateral channels 4^b left between the said 75 partitions 2 and the sides of the casing 1.

If several partitions are used, these are graduated as shown in Fig. 1, the central partitions being higher than those on the side.

80 Owing to this arrangement, and the source of heat is located in the lower centre of the apparatus, an ascending current will be produced in the centre channels 3 by the thermosiphon principle, and a descending current in 85 the lateral channels 4, so that the water will circulate in a closed circuit as indicated by the arrows in the drawing.

In the event of the electric current being utilized, the resistances 5 are arranged horizontally and crosswise from one of the radiators to the other, and each resistance is connected at one end to one of the leads conveying the current and at the other end to a contact 6 over which passes a brush 90 operated by a handle in the manner of a rheostat, so as to permit of engaging in the circuit 1, 2, 3, 4 resistances, etc. at will.

On the first stop, when only one resistance is in action, the radiator is heated gently and 100

its temperature will keep in the vicinity of 30 degrees C. (in a room of fifteen degrees), whereby the current consumption is a minimum.

5 On the last point, all resistances are in action and the water may approach boiling point. This is the "starting-up" position when it is desired rapidly to raise the heater to the temperature required. Once this degree has been reached, the handle is turned back onto such contact as will give the degree of heat it is proposed to maintain.

10 On each stop may be marked the approximate degree of temperature ensured by the 15 radiator in continuous operation.

15 The resistances may be in the shape of blades, of bars, or of cylinders; they may be arranged in different manners on the walls or inside the container. The neutral wire, 20 or earth lead, may be connected to the body of the apparatus, and thus to one of the resistances. The tension wire is connected to the regulator, and through the latter to the insulated stops corresponding to the other 25 ends of the resistances. This arrangement affords the possibility of utilizing resistances immersed in the water direct, and thus of obtaining a higher degree of efficiency.

30 The heating may equally be ensured by a range of gas burners or by spirit burners, or by hydrocarbons of any kind.

35 Whereas, in the event of heating by electric resistances 5, the bottom 8' may be flat if heating is ensured by a range of burners 7, the bottom must not be flat, because it would be licked by the flame over the whole of its surface and the current descending through the channels 4 would establish itself with difficulty. It is, therefore, expedient to 40 keep the channels conducting the downward bound current away from the flame and below its level, by making the profile of the bottom 8 in the shape of an inverted trough, or camel's hump, or alternatively triangular, 45 thus promoting the circulation of the water by thermosiphon.

50 In order to permit of series manufacture, a single type of elements of the latter kind may be produced, as shown in the drawing, which will be just as useful for heating from the outside by a burner as for heating from inside by electric resistances.

55 The flat and water-proof casings 1 are made by joining (Fig. 2) two metal sheets of any kind 9, 10 (sheet lead, for example aluminium) separated one from the other by an appropriate distance (5 to 10 millimetres) and folded (and soldered if required) at their edges 15.

60 The partitions 2 ensure the necessary distance between the said plates; they may be fixed simply by two rivets.

65 The Figure 2 shows a radiator formed of several integral casings 1 placed one before the other and linked up by pieces of trade

pattern tubes of 2 to 3 cm. length. At the top, they may communicate by a single passage in the centre, or by two at the side as shown in Fig. 1.

The upper communication tubes 11, of small diameter, serve to conduct the steam and the gases; they may contain a metal stay to give firmness to the whole structure.

They can be replaced by a tube situated at the upper, lateral part of the radiator and 75 connected to each element.

The lower tube 12 is of ampler proportions in order to accommodate, if required, electric resistances 5 (alternative of an electric radiator) or offer sufficient surface to 80 the flame. It appears to be preferable to give this lower passage a semi-circular or triangular shape.

In the event of an electric radiator (Fig. 2) a threaded bronze ring 16 is soldered on 85 to the front of the first casing 1^a, and on this is screwed a cap 17, to which are fixed the resistances. The axis 18 of the support holding the resistances 5 may be lodged in 90 a centre piece 19 fixed to the external plate of the last element 1^c.

Above this radiator, and a little outside the first casing 1^a, an expansion chamber 13 is provided formed by two hemispheres 95 screwed or the like the one to the other, whereby the lower half may at the same time be used as a funnel for filling up. A piece of tubing 14, preferably bent slightly upwards (for filling under pressure) is 100 joined to the upper half; an alarm whistle may be fitted to it through which the steam must escape and which will thus prevent any possibility of internal pressure and, consequently, all danger of explosion. 105

As soon as the steam reaches a certain pressure, a penetrating alarm will notify that it is time to reduce the heating. The said alarm whistle is likewise able to warn against a shortage of water, or against a 110 fault in the water circulation, if it is heard without the heating being full on.

Thus the air is moistened without excess to obtain agreeable and healthy heating.

In practice, the water is not heated above 115 70 to 80 degrees C., and adequate condensation is ensured by placing the vessel 13 outside the current of hot air rising around the walls of the first casing 1^a, but to the contrary, within the current of non-heated 120 air carried along—by the current of hot air, thus facilitating condensation.

Instead of a condensation bulb 13, a small expansion chamber 21 (Fig. 7) may be shaped out of the top wall of the casing, to 125 which a tube 22 is joined through which the steam and gas may escape. This bent tube leads down to below the radiator and ends there in a condensation coil 23 with a slight inclination. Condensation is as- 130

- sisted therein by the current of cold air which rises to be heated in contact with radiator. The water, thus distilled, is collected in a dripping dish 24 and may thus be filled in the radiator. The condensing pipe may be placed, as the sphere of condensation, at the upper and lateral part. Water condensed therein descends again into the radiator.
- 10 Filling of the latter is in such case performed through a stopper 25 analogous to those of the automobile radiators, and situated below the beginning of tube 22.
- 15 Where heating is ensured by a range 7 or single burners, the coil 23, situated below the said burner is separated from it, in order to screen it from the heat radiated, by a perforated grate or strip 26 which allows the air to pass.
- 20 In order not to impede the expansion of steam and gases in each integral unit 1, care should be taken that the water level does not rise above the upper communicating tubes 11. There is also provided, somewhat 25 below these tubes, either on one of the sides or the front of the first element 1^a (Fig. 2) a small drain plug 20, which is only opened when filling up, to show when the water has reached the proper level.
- 30 In order to permit a series manufacture it is preferable to constitute the partitions of the casing, not in the way of walls fixed thereto by rivets but by forming grooves in a certain height of each of the plates 9, 10, 35 the bottoms of these grooves 33 being brought together by means of rivets 34 or the like. Such grooves-partitions increase the firmness and the reliability of the plates of the casing.
- 40 The rivets 34 are advantageously constituted (Fig. 5) so as to present eyes for the passage of tightening rods 35 or the like traversing the stay-sleeves 35', of appropriate length and keeping two neighbouring 45 elements at a chosen distance.
- For such fitting the elements, whose number varies according to the requirements, are instantaneously interchangeable in case of deterioration of one of them.
- 50 The standard element can be manufactured with aid of a die pressing at one time:
- (a) the two groove-partitions 33, the rivets 34 being mounted at the extremities of these parts;
- 55 (b) the borders destined to be either hooked on as shown in 15 or soldered as indicated at 15';
- (c) the two central communication orifices (the upper can be kept smaller) and around 60 these two orifices 11, 12 two feeble annular basins 36 destined to receive a metal piece 37 impeding the flattening of the casing during assembling destined to secure a tight joint (Fig. 6).
- 65 At the level of the orifices of communica-
- tion 11, 12 thick and perforated rings 37 are placed within the annular basins 36.
- These rings are:
- (a) perforated in order to permit the circulation of water or steam through the 70 communicating orifices, and they are (b) thick in order to offer sufficient resistance during tightening serving to assure a tight joint between the outer rings 11 or 12 and the walls 9, 10 of the element. 75
- The four tightening rods 36 and their stay-sleeves 35 placed at the extremities of the partitions 33 suffice to assure perfect rigidity. Resistances 5 may be fixed on threaded rods 18 and redrawn therewith in 80 case of need, independently of the assembled casings. Tightness is secured with aid of nuts on the extremities of the threaded rod 18.
- In certain cases it may be advantageous 85 to add in a tank or casing containing two partitions 2 (or such by grooves 33) of the kind as represented in Fig. 1, a medium partition 2' so as to divide the casing into two half casings 1', possessing one partition 2 90 only (or one division 33) engendering a water circulation by thermosiphon water ascending at 3 and descending at 4.
- With the aid of these half-casings radiators can be erected, presenting a general 95 circular or half-circular form by adopting a radial arrangement of the elements, as indicated in Figs. 3 and 4, the half-casings having their faces either arched or bent as shown at 1'' (Fig. 4). 100
- In a radiator forming a complete star numerous bent elements facilitating (for example for its ignition) the access to the burner 7 of circular or other form the burner 7 is in contact or not with the internal 105 edge 8' of the half-casings; the circular form is particularly advantageous for the heating of the gas essence.
- Each half-casing 1 possesses its heating flame (or its resistance,) according to the 110 case.
- The communication of the casings between themselves may be established at the upper part as in the foregoing case by means of communication tubes 11 bent suitably and connecting each element to the expansion chamber or by a central upper communication; at the lower end communication tubes 12 (containing eventually the resistances 5) may effect the form of a torus, 115 complete, as in Fig. 4, so as to have neither a first nor a last element. 120
- All tubes establishing the lower communication 12 may be, as shown in Fig. 3, replaced by a single sheet metal body 12', 125 round or otherwise shaped and presenting at its upper part radial saw-cuts for the adaptation of the lower properly cut ends or bottoms of the half-casings, water rising across the said saw-cuts. 130

This body forms hence a boiler, containing eventually the electric resistances.

According to a modified form of the subject-matter of the invention the radiator 5 may consist, instead of the flat casings 1 with inner partitions 2 forming channels for the ascending and descending current, of vertical water tubes 3', 4' (Fig. 7) connecting a lower reservoir 28 containing the 10 source of heat (electric resistances) or licked by the heat (range 7), to an upper reservoir 29 the bottoms 30, 31 being formed in such manner that water circulates owing to difference of densities, from bottom to 15 top in central tubes 3' and from top to the bottom in the lateral tubes 4', owing to the stepping of these tubes (stepped partitions 2), and to the effect of thermosiphon.

In this manner, tubes 3' are provided at 20 the central upper part of the curved bottom 30, hot water rising through them to the summit of the convex bottom 31, whereas laterally tubes 4' are provided on the inclined bottom 4', cooled water descending through 25 these tubes in order to get warm by the contact with the heat source, which is constituted, as said, either by electric resistances or by burners 7 and the heated wall 8.

Fig. 7 shows the principle of such apparatus containing eight tubes.

Owing to the absence of interior pressure, the radiator can be built up by elements of a very feeble thickness and of any metal. This apparatus secures a very reduced 35 cumberment and weight and very great heating surface.

Hence the invention permits the establishment of light and small apparatus procuring a healthy and very clean heating without any danger whatsoever.

In order to avoid filling up with water and all steam emission into the compartment, a single expansion basin or the like may be provided, communicating at will 45 with one or several radiators utilized in the same apartment.

For this purpose, in each compartment a canalization is provided, having a feeble diameter and leading to the said expansion 50 body.

The canalization may terminate by a cock (similar, for example, to the gas cocks) and the connection with the radiator may be established by a short piece of a tube of 55 india rubber directed obliquely upwardly. It is possible to provide several "cocks" in the same apartment, for a radiator or radiators.

Since it is of interest to have light, portable radiators with walls of feeble resistance, the expansion basin or vessel for these radiators ought to be arranged at a distance therefrom, not surpassing one to two meters.

The same devices may be utilized for heating 60 of railway carriages; it is for example

possible to arrange radiators having a rectangular section below the seats and to provide at their upper parts or borders the communication tubes staying the radiators connected to an expansion vessel situated for 70 example in the W. C. of the car. The necessary current is derived either from the line (electric traction) or from a dynamo driven during run (like the light-dynamo) or by a turbo-dynamo placed on the locomotive. 75 Not only the heating of the car but also the heating of each compartment may be regulated by the travellers themselves.

In order to heat the train at stays, it will suffice to provide wall plugs in stations and 80 on shunt-lines, said wallplugs deriving the current from the substation or the like. Hence, the apparatus will work at stays as well as during run, independently of the kind of traction employed.

Finally, in order to couple the apparatus with a radiator with wings, of the usual kind, hot water is led off at the upper part of the apparatus according to the invention, while the back flow is established at its lower 90 part. In such manner the present radiator can play the rôle of a boiler in central heating plants.

The radiator can also have the form of a simple water kettle or of a foot-warmer containing the resistances at their lower parts. The kettle or the like may be connected to the expansion vessel of the car (train, tramway and so on).

What I claim is:—

1. In a radiator, bodies to contain water, bottom parts for said bodies, raised in their central parts and stepped downwardly with their lateral parts, channels in said bodies following with their lower extremities the 105 outlines of said bottom parts to ensure a water circulation due to thermosiphon action in said bodies, heating sources for said bodies, to heat their central water columns, and means to interconnect said bodies and to advertise abnormal working conditions.

2. In a radiator, bodies to contain water, vertically grooved parts in said bodies, in their opposite vertical walls, to form partitions in said bodies, means to connect to each other said grooved parts, stepped bottoms for said bodies, means to heat their water, means to permit the expansion of water, and means to advertise abnormal working conditions.

3. In a radiator, bodies to contain water, vertical stepped parts in the vertical opposite walls of said bodies, to form partitions in said bodies, tubular rivets to the opposite stepped parts, stay-sleeves between the parallelly placed bodies, tightening rods passing through said stay-sleeves and said hollow rivets, to assemble the bodies, means to heat the central water column in each 125

- body, communication means between the bodies, means to permit expansion of water and means to signalize all abnormal working conditions.
- 5 4. Circulation radiator for water of the type described, comprising a series of elements formed by vertical conduits connecting two chambers, an upper and a lower, the conduits having substantially the same 10 length and being stepped and connecting the bottom parts of the chamber in opposition to each other, said conduits being curved towards the top in a regular fashion and being extended so that the water heated in the 15 lower chamber through a suitable source of heat, travels on the extended inclined walls of the top of the lower chamber when it rises to arrive at the central conduits of higher location, while in the upper chamber 20 the cooled water flows downward on the inclined walls to arrive at the lateral conduits which are located farther down. 25 5. Radiator for water circulation as set forth in claim 4, in which each radiator element is formed by the assembly of two thin metallic plates joined together at their margins to form a very flat tight casing in the interior of which vertical partition walls or baffles direct the circulation of the wall. 30 6. Radiator for water circulation as set forth in claim 4, in which each radiator element is formed of thin metallic plates joined at their edges to form a tight and very flat casing, said casing being connected to each 35 other at the bottom and at the top by conduits, the upper conduits furnishing a passage for the vapor and gases while the lower conduit, having a greater cross section, contains a source of heat if necessary. 40 7. Radiator for water circulation to be used in connection with a condensing apparatus, or expansion receptacle, the elements of which are self-contained and have heating and circulating means of their own, 45 characterized in this that in each element formed of metallic thin plates united to present a flat, tight casing, the upper and lower chamber of each casing are connected by vertical conduits of substantially the same 50 length and stepped in such manner that the water heated in the lower chamber of the casing by some suitable source of heat travels along the slanted extending parts of the top of the lower chamber to arrive in an ascending movement at the central conduits of 55 higher location, while in the upper chamber, the cooled water travels downward on the slanting walls to arrive at the lateral conduits of lower location and comprising a 60 condensing chamber placed slightly outside the upper part of the first casing beyond the current of heated air which rises and placed about this casing and contrasting therewith, the cooler current of air taken along by the 65 same travels in the said chamber being 65
- formed of the assembly of two shells, the inner space whereof serves for filling and the upper whereof carries the pipe for the escape of the vapors.
8. A radiator for water circulation as 70 claimed in claim 7, in which the elements have an odd number of cells and the central cell is extended for dividing the casing in two half portions.
9. Circulating water radiator as set forth 75 in claim 7, in which several half casings are radially disposed to provide an apparatus of generally cylindrical form, certain of the casings having their faces arched to facilitate access to a circular burner. 80
- In witness whereof I affix my signature.
